UNITED STATES PATENT OFFICE.

SAMUEL TROOD, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

SNAP-SWITCH FOR SAD-IRONS AND THE LIKE.

1,248,575.

Specification of Letters Patent.

Patented Dec. 4, 1917.

Application filed January 28, 1913. Serial No. 744,678.

To all whom it may concern:

Be it known that I, SAMUEL TROOD, a citizen of the United States, and a resident of Edgewood Park, in the county of Allegheny and State of Pennsylvania, have invented a new and useful Improvement in Snap-Switches for Sad-Irons and the like, of which the following is a specification.

My invention relates to electric switching devices, and it has special reference to snap-switches adapted for use in the handles of sad irons or other switch-controlled electric apparatus.

One object of my invention is to provide a snap switch in the handle of a sad iron or other electric appliance which shall have a quick, positive and reliable action and shall be located in the manner and place most convenient for the user of the iron.

Another object of my invention is to provide a switch of compact and rugged construction which shall also be inexpensive to manufacture.

A further object of my invention is to provide a magnetic blowout coil in connection with the relatively movable contact members of the switch mechanism for extinguishing arcs formed by interruption of the circuit.

Heretofore, switches associated with the handles of sad irons and similar implements have been of the ordinary blade or some other slow-moving type, with the consequent burning of contacts and other deleterious features which have rendered the action of the switches more or less unreliable. Moreover, the switches provided have been bulky and expensive, entailing difficulty of installation and repair.

According to my invention, I provide a switch of a quick-break type, commonly known as a "snap switch". The mechanism is constructed to give an accelerated motion to the movable switch contact member and, moreover, will remain in the open or closed position with no danger of rebounding or of sticking in an intermediate position.

One of the features of my invention is the convenience of the switch by reason of the position and mode of operation thereof. The push button operating the switch is located in the forward end of the handle and moreover operates in a vertical

plane, thus being directly adjacent to the natural position of the thumb and forefinger of the operator.

An illustrative embodiment of my invention, as applied to an electrically heated sad iron, is shown in the accompanying drawing, in which Figure 1 is a view in side elevation, partially in section, of a sad iron embodying my invention; Fig. 2 is an enlarged view, partially in elevation and partially in section, of the switch mechanism, showing the construction thereof; and Fig. 3 is a view of a modification of my invention employing a magnetic blowout coil in proximity to the switch contact surfaces, thereby eliminating all possibility of an extended arc.

Referring to the drawing, a sad iron 1 comprises a hot plate 2, an incasing member 3, an electric heating element 4 contained therein, a tubular handle 5 disposed on supports 6, a terminal-board 7 provided with binding posts 8, 9 and 9^a, a switch mechanism 10 disposed in the front end of the handle, and supply conductors 11 for making connection to an exterior source of electrical energy. The above-named parts, other than the handle 5 and the contents thereof, are old and well-known in the art and will not further be described. It should be understood, however, that my invention need not be restricted to use in the handle of a sad iron, but may be employed in other electrical devices.

The supply conductors 11 extend through the open rear end of the handle 5, and are connected to binding posts 8 and 9 of the terminal board 7. Leads 12 extend from the binding posts 8 and 9^a through the rear handle support 6 to the heating element 4, and leads 12^a connect the binding posts 9 and 9^a to the contact terminals of the switch mechanism 10.

The switch mechanism 10 comprises a vertically disposed push button 13, and a conducting shell 19 concentrically disposed around the button 13 and expanded at one end to form an annular recess 20 for a garter spring 21 which surrounds and engages the button 13.

A plurality of vertically alined openings 22 are provided in the handle 5, and the push button 13 is disposed to project through said openings, thus adapting the

switch for operation by the user of the iron. The push-button 13 comprises four sections, namely: two outer cylindrical sections 16 and 17 composed of insulating material and 5 adapted to extend through the openings 22 in the handle 5, a frusto-conical section 15 of insulating material, and a frusto-conical section 14 of conducting material, provided with an integral outwardly-projecting end 10 flange 23 for making contact with the upper wall of the recess 20 of the shell 19. The sections 14 and 15 are suitably held together to constitute a double frusto-conical cam, and the conducting portion 14 is connected 15 to the binding post 9 by one of the leads 12^a. The lower end of the shell 19 is connected to the binding post 9^a by the second lead 12^a. Suitable members 24 of insulating material inclose a longitudinally-disposed 20 supporting bar 25 attached to the body of the handle 5 for holding the switch mechanism 10 and terminal-board 7 rigidly in position.

In the modification shown in Fig. 3, the 25 push-button 13 and a shell 26, provided with a recess 27 of slightly different shape from the recess 20, are inclosed by a blow-out magnet coil 28 for extinguishing arcs produced by the separation of the flange 23 and 30 the top wall of the recess 27, which two members are connected to the opposite line terminals through the blowout coil 28 and the heater element 4, as in the switch mechanism first described.

35 Assuming the switch to be in the closed position, as shown in the drawing, the operation, when opening the circuit, is as follows: The end of the push button 13 that projects through the lower opening 22 in 40 the handle 5, is pressed inwardly against the force exerted by the garter spring 21 upon the frusto-conical section 14 until the plane 18 of the cam passes the central plane of the spring, whereupon the contact flange 45 23 is snapped into its "off" position by the contraction of the spring.

In closing the circuit, the upper end of 50 the button 13 is pressed inwardly against the force of the spring 21 exerted against the surface of the section 15 until the plane 18 passes the central plane of the spring, whereupon the spring pressure upon the surface of section 14 will move the flange 23 into contact with the outer surface of the 55 recess 20 with a snap action.

I do not wish to be restricted to the specific structural details herein set forth, but desire that only such limitations shall be imposed as are indicated in the appended 60 claims.

I claim as my invention:

1. An electric switch embodying a contact-carrying actuating member provided with a cam comprising oppositely-disposed frusto-conical sections one of which is of 65 conducting material, a coöperating stationary contact member surrounding said actuating member, a recess disposed near one end of said stationary member, and a resilient tension member disposed within said recess and engaging said cam for giving an 70 accelerated movement to said actuating member.

2. An electric switch embodying a contact-carrying actuating member provided 75 with a cam comprising oppositely-disposed frusto-conical sections one of which is of conducting material, a coöperating stationary hollow contact member concentrically disposed around said actuating member 80 and provided with an annular integral recess at one end, and a garter spring disposed within said recess and engaging said cam for giving an accelerated movement to 85 said actuating member.

3. An electric switch embodying a contact-carrying reciprocating member provided with a cam comprising oppositely-disposed frusto-conical sections one of which is of insulating material and the 90 other of which constitutes a movable contact member, a coöperating tubular stationary contact member surrounding said reciprocating member and having an annular recess near one end, and a garter spring 95 disposed within said recess and engaging said cam for giving an accelerated movement to 100 said reciprocating member.

4. An electric switch embodying a contact-carrying reciprocating member provided 105 with a cam comprising oppositely-disposed frusto-conical sections one of which is of insulating material and the other of which constitutes a movable contact member, a coöperating tubular stationary contact member concentrically disposed around said reciprocating member and provided with an annular integral recess, and a garter spring disposed within said recess and engaging said cam for giving an accelerated movement to 110 said reciprocating member.

In testimony whereof, I have hereunto subscribed my name this 23rd day of January, 1913.

SAMUEL TROOD.
